UNITED STATES PATENT OFFICE.

JOSEPH S. DALE, JR., OF NEW YORK, N. Y.

STABILIZER FOR FLYING-MACHINES.

1,214,901.

Specification of Letters Patent.

Patented Feb. 6, 1917.

Application filed March 25, 1915. Serial No. 16,937.

To all whom it may concern:

Be it known that I, JOSEPH S. DALE, Jr., a citizen of the United States, and a resident of New York, Bronx borough, in the 5 county of Bronx and State of New York, have invented certain new and useful Improvements in Stabilizers for Flying-Machines, of which the following is a specification.

10 This invention relates to stabilizers for heavier than air flying machines.

The object of my improvements is to provide power actuated, automatically governed stabilizing mechanism, the governing 15 means being efficient to automatically right the machine whenever it becomes laterally out of balance, and to automatically bring the machine to its proper angle of lateral inclination whenever it travels in a horizontally curved path.

Another object of my improvements is to provide means for manually controlling the governing means, when so desired.

A further object of my improvements is 25 to provide means for locking the manual controlling means in any desired position.

A still further object of my improvements is to provide means whereby, when the operator releases his control of the 30 manual controlling means and of the locking means, the several manually operated means will automatically return to their normally inactive positions and thus free the governing means for automatic operation.

35 Other objects will appear hereinafter.

With these objects in view the preferred form of my improvements is illustrated in the accompanying drawings wherein—

40 Figure 1 is a sectional plan view on line 1—1 of Fig. 2, showing in detail the stabilizer plane actuating and governing mechanism of my improved device. Fig. 2 is a cross sectional elevation taken on line

45 2—2 of Fig. 1. Fig. 3 is a sectional view of part of the clutch operating mechanism shown in Figs. 1 and 2. Fig. 4 is a transverse sectional view of the lower portion of that which is shown in Fig. 2. Fig. 5

50 is an elevation partly in section, showing details of the manual controlling and locking means of my improved device. Fig. 6 is a perspective plan view illustrating the means operatively connecting the manual

55 controlling means of Fig. 5 with the governing means. Fig. 7 is a partial plan view

similar to Fig. 1, but illustrating a modification of the governing means shown in said figure, said view being taken on line 7—7 of Fig. 8. Fig. 8 is a sectional elevation of what is shown in Fig. 7 and taken on line 8—8 of said figure. Fig. 9 is a detail of the governing means shown in Figs. 7 and 8. Fig. 10 is a rear perspective view of a flying machine embodying the application of my improvements. Figs. 1, 2, 3, 4, 7, 8 and 9 are to one scale; Figs. 5 and 6 are to a smaller scale; while Fig. 10 is to a greatly reduced scale.

Before describing the invention in detail I desire to have it understood that the invention is not limited to the particular construction and arrangement of parts which I have illustrated and shall hereinafter describe, and that various changes may be made within the scope of the claims without departing from the spirit of the invention, and that the phraseology which I employ is for the purpose of description and not of limitation.

My improvements are herein illustrated as applied to that type of flying machine commonly known as a biplane, but it will be obvious to those skilled in the art that said improvements are equally applicable to other known forms of heavier than air flying machines and are not restricted to the particular type illustrated.

The actuating and governing means of my improved device are illustrated in Figs. 1 and 2 of the drawings as contained in a casing, 2. Rotatably mounted in bearings 3, 4 of said casing, are clutch shafts 5, 6 respectively. Shaft 5 is continuously rotated, whenever the flying machine prime motor is in operation, by means of gear 7, fixed to said shaft and intermeshing with gear 8, rigidly mounted on driving shaft 9 of said prime motor. Shaft 5 drives shaft 6, at the same speed and in the same direction, by means of equal sprockets 10 and 11, fixed to said shafts respectively, and geared together by means of sprocket chain 12, mounted on said sprockets. Coaxial with shafts 5 and 6 are shafts 13, 14, rotatably mounted in bearings 15, 16, respectively, of casing 2. Said shafts 13 and 14 are geared together by equal gears 17, 18, fixed to said shafts respectively.

I will designate in a general way, the two 110 friction disk clutches shown, by the numerals 19, 20 respectively and, as said

clutches are alike in function and parts, a detail description of one will suffice for both. Loosely mounted on, but engaging a spline in shaft 5 for rotation therewith, is a series 5 of friction disks 21. Also loosely mounted on said shaft 5 and alternating with said disks 21, is another series of friction disks 22, said disks 22 engaging a spline or groove in the interior of cup-like extension 23 of 10 shaft 13 for rotation with said shaft. Loosely mounted on shaft 13 and rotatable therewith is a collar 24 having pins 25, preferably four in number, which reach through holes in the wall of said cup-like extension 15 23 and engage the face of adjacent friction disk 22. Also loosely mounted on said shaft 13 and closely adjacent to collar 24 is another collar 26, a thrust ball bearing 89 being provided between the adjacent portions 20 of said collars 24 and 26. Collar 26 is held against rotation by forked member 27, extending outwardly to the right from support 28 of governing weight 29, said support being pivotally mounted at 30 in upstanding arm 31 of casing 2. The inner surfaces 35 of forked member 27, formed concentric with pivot 30, slidably engage corresponding concentric surfaces 86 of collar 26, respectively. 25

30 Weight support 28 extends through suitable openings in the top and bottom walls of casing 2, and immediately without said bottom opening and between the adjacent surfaces of said casing and said support, are provided ball bearings 32 for guiding said weight support 28 in its slight, lateral movements, said ball bearings also being concentric with said pivot 30. Wedge members 33 are rigidly mounted on the inboard vertical 35 face of forked member 27, the inclined surfaces 34 of said wedges slidably engaging corresponding inclined surfaces 35 on collar 26, respectively. Wedges 33 are adjustable on forked member 27 by means of slots 40 36 in said fork and binding screws 37 passing therethrough and threading into said wedges. Fork 38 extends outwardly to the left from weight support 28 and, as the action of the wedges on said fork upon the 45 collars mounted on shaft 14 is in all respects similar to that of the corresponding parts just described in connection with shaft 13, a further description of said fork 38 and said collars is deemed unnecessary. On the 50 outboard end of shaft 13 is fixed drum 39 for operating the stabilizer planes. 55

60 Thus, when weight support 28 is caused to move to the right, inclined surfaces 34 of wedges 33 on fork 27 will mount the corresponding inclined surfaces 35 of collar 26, and cause pins 25 of collar 24 to press friction disks 22 of shaft 13 and friction disks 21 of shaft 5 together and against shoulder 40 of shaft 5, when shaft 13 and drum 39 will rotate in the same direction as said

shaft 5. Or, when weight support 28 is caused to move to the left, the inclined surfaces of the wedges on fork 38 will then cause the several parts of friction clutch 20 to coact and said clutch to operate, when shaft 14 will rotate in the same direction as shafts 5 and 6 and, through gears 17, 18, will cause shaft 13 and drum 39 to rotate in the direction opposite to that of said shaft 5. 70 Drum 39 is operatively connected with stabilizer plane 41 by means of a flexible wire, wrapped several times around said drum and the two ends of which, 42, 43, extending outwardly to the left and over suitable guide pulleys, are connected to the top and bottom of said plane, respectively. Stabilizer plane 44 is also operatively connected with said drum 39 by means of another flexible wire wrapped around said drum and the two ends of which, 45, 46, extending outwardly to the right and over suitable guide pulleys, are connected with the top and bottom of that plane, respectively. Said planes 41, 44 are normally horizontal and are pivotally mounted at their front portions to the 80 main frame of the flying machine in such manner that their rear portions may be oscillated up or down by means of the wire connections just described and fastened to said rear portions, as wires 42, 43 to plane 90 41. The arrangement of these connections is such that when drum 39 is rotated, stabilizer planes 41 and 44 will be caused to move each in a direction opposite to that of the other. See Figs. 1, 7 and 10. 95

100 The means for manually controlling the governing means of my improved device are illustrated particularly in Figs. 5 and 6 of the drawings, wherein steering wheel shaft 47 is shown rotatably mounted in sleeve 48, 105 which again is rotatably mounted in bearings 49, 50, supported on the main frame of the flying machine. Fixed to the upper end of said sleeve 48 is hand wheel 51, and to the lower end thereof is fixed winding drum 110 or pulley 52. A flexible wire is wrapped several times around said drum 52 and the two ends of which, 53, 54, extend respectively, rearwardly and outwardly through guide bolts 55, 56 and around guide pulleys 115 57, 58. The ends of wires 53, 54 are connected to tension springs 59, 60, respectively, the opposite ends of said springs being fastened respectively, to eye-bolts 61, 62. Said guide bolts, guide pulleys and eye-bolts are 120 all secured to the underside of lower plane 63 of the flying machine. Also connected to the ends of wires 53, 54, respectively, are short lengths of chain 65, 66, the other ends of which are connected respectively, to tension springs 67, 68, and the opposite ends of which springs are connected to weight 29 of the automatic governing means. Said chains 65, 66 and springs 67, 68 are arranged with sufficient slackness to allow weight 29 130

normally to have perfect freedom of movement.

Upstanding from drum 52 and integral therewith is receiving member 69 of a friction cone clutch. Adjacent thereto and for frictional engagement therewith is cone member 70 of said clutch. Said cone member 70 is loosely mounted on sleeve 48 and is held against rotation thereon and in its normal position of disengagement with clutch member 69, by means of pins 71 extending outwardly therefrom and in engagement with slotted holes in the surrounding portion of foot-lever 72, pivotally mounted at 73 in arm 74 upstanding from bearing 50. The other end of foot-lever 72 extends over the front edge of lower plane 63 of the flying machine and is held in its normal position by compression spring 75.

Thus, when hand-wheel 51 is rotated in clockwise direction, wire 53 will wind upon said drum 52 and wire 54 will unwind therefrom, causing spring 59 to distend and the slackness of chain 65 and spring 67 to be taken up, and further causing said spring 67 to distend, until tension is exerted upon weight 29, moving said weight and weight support 28 to the left, when clutch 20 of the governing means will operate. Upon hand-wheel 51 being rotated in anti-clockwise direction, weight 29 and weight support 28 will be moved to the right, in a manner similar to that just described, when clutch 19 of the governing means will operate. Stop members 76, 77, rigidly secured to wires 53, 54, for engagement with guide bolts 55, 56, respectively, are provided for limiting the movement of said wires and thus gaging a maximum amount of tension to which said springs 67, 68 may be subjected. When drum 52 has been rotated to a position causing tension on either of springs 67, 68, it may be locked in said position by operating cone clutch member 70 to engagement with clutch member 69 of said drum 52 by means of foot lever 72, and may be held so locked at the will of the operator, thus freeing wheel 51 from the need of hand control. When the hand-wheel 51 and foot lever 72 are both released, drum 52 and wires 53, 54 will be caused to return to their normal positions of Fig. 6 by means of tension springs 59, 60 seeking a state of equilibrium.

In Fig. 2 of the drawings weight 29 of the governing means is shown as being pivotally supported at 30. Such pivotal construction is not essential to the operation of my improved device and in Figs. 7, 8 and 9, I have illustrated a modification of this portion of the mechanism. Therein governing weight 78 is shown as mounted for free but slight lateral movement within casing 2 and between shafts 13, 14. Said weight is at all times supported and is guided in movement by means of forked members 79,

80 which extend outwardly therefrom a sufficient distance to overlap lugs 81, 82 extending inwardly from the side walls of casing 2. Between the adjacent faces of said forks and said lugs, ball bearings 83 are provided in V shaped grooves in said faces. Arm 84 reaching downwardly from weight 78 and extending through a suitable opening in the lower wall of casing 2, is provided for receiving the ends of tension springs 67, 68. The lateral movement of this governing mechanism being in a straight path, the co-engaging surfaces of the collars loosely mounted on shafts 13, 14 and of forks 78, 80, respectively, are plane surfaces, as inner surfaces 87 of fork 79, and corresponding surfaces 88 of collar 26 of shaft 13. As the construction and operation of the governing means of Figs. 7 and 8 are in all other respects similar to those of the governing means of Figs. 1 and 2, a further description of the showing of said Figs. 7 and 8 is deemed unnecessary.

The operation of my improved device is as follows:

It will first be understood that the actuating and governing means, shown in Figs. 1, 2 and 7, 8, are so constructed as to operate freely yet with a minimum of lost motion, so that clutches 19, 20 will quickly respond to the slight movements of weight 29, or weight 78. Also, the wedge members which actuate clutches 19, 20, are so adjusted as to have their inclined surfaces loosely engaging the corresponding inclined surfaces of the respective collars on shafts 13, 14, so that any motion of governing weight 29, or governing weight 78, will tend to operate one or the other of said clutches 19, 20.

The biplane now being in flight and the prime motor in operation, shafts 5 and 6, driven from motor shaft 9, will continuously rotate in the direction of their respective arrows, as shown in Fig. 1. Also, assuming that said biplane is in normal position laterally, weight 29, or weight 78, will be in central position, clutches 19, 20 will be out of operation, and shafts 13, 14, drum 39 and stabilizer planes 41, 44, will be at rest. If now for any cause the biplane should incline downwardly to the right, governing weight 29, or governing weight 78, will move also to the right, causing the inclined surfaces 34 of wedges 33 to mount the corresponding inclined surfaces 85 of collar 26, 120 thus moving said collar 26 and collar 24 slightly lengthwise of shaft 13 and causing pins 25 of said collar 24 to press disks 22 of shaft 13 and disks 21 of shaft 5 together and against shoulder 40 of said shaft 5, 125 when clutch 19 will be caused to operate and shaft 13 to rotate in the same direction as shaft 5. Collar 26 being held against rotation on shaft 13 and at the same time pressed toward collar 24, which collar 130

4

tates with said shaft 13, the adjacent faces of said collars are enabled to pass freely by one another by means of thrust ball bearing 89 therebetween. Drum 39, fixed to the out-
 5 board end of shaft 13, now rotating in clockwise direction, will wind flexible wire 46 thereon and unwind wire 45 therefrom and, at the same time, wind wire 42 thereon and unwind wire 43 therefrom, thus pulling stabilizer
 10 plane 44 downwardly and stabilizer plane 41 upwardly, when the biplane will speedily become righted. Or, if the biplane should incline downwardly to the left, said governing weight will also move to the left and, in the same manner as that just described in connection with clutch 19, will cause clutch 20 to operate and to rotate shaft 14 in the same direction as shafts 5 and 6 and, through gears 18, 17, fixed to shafts 14, 13, respectively, will cause shaft 13 to rotate in the direction opposite to that of shafts 5 and 6. Drum 39, now rotating in anticlockwise direction, wire 43 will wind thereon and wire 42 will unwind therefrom and, at the same time, wire 45 will wind thereon and wire 46 will unwind therefrom, thus pulling stabilizer plane 41 downwardly and stabilizer plane 44 upwardly, when the biplane will again become righted.
 15 30 Again, if the operator causes the biplane to travel in a horizontally curved path, curving sharply to the left for instance, said governing weight will then through centrifugal action move to the right, operating clutch 19 and rotating drum 39 in clockwise direction, thus lowering stabilizer plane 44 and elevating stabilizer plane 41, when the right hand end of the biplane will be elevated and the left hand end depressed, until such angle of inclination is reached as will cause said biplane to be in a state of equilibrium, relatively to the degree of curvature of its path and the speed with which it is traveling, when said governing weight will come to its central position and thus allow the stabilizer planes to assume their normal, idle positions. Or, if the operator should cause the biplane to travel in a horizontally curved path to the right, the governing weight will then move to the left, operating clutch 20, when said drum 39 will rotate in anti-clockwise direction, thus lowering stabilizer plane 41 and elevating stabilizer plane 44, when the biplane will incline downwardly to the right until such angle is reached as will again bring the biplane to a state of equilibrium relatively to the curvature of its path and the speed of its travel, and the governing weight and stabilizer planes will come to their normal idle positions, as described above.

55 60 65 My improved device is of such nature that it responds proportionately to the work it is called upon to do. Clutches 19, 20 are sensitive in operation and may gradually vary in

action, from doing no work to that of their full capacity. Governing weight 29, or governing weight 78, has practically no lost motion, so that any movement of said weight will tend to operate either one clutch or the other. If said weight moves or tends to move with but little force the clutch acted upon will but lightly operate. If said weight tends to move with greater force the clutch acted upon will do correspondingly more work. Hence, the device being under automatic control, if the biplane should suddenly incline downwardly in lateral direction, the amount of power transmitted will be proportional to the angle of inclination and, as the biplane gradually becomes righted, the amount of power transmitted will gradually lessen until it ceases altogether on the biplane coming to its normal position. Also, such sudden inclination of the biplane causes the weight operating the clutches to act with greater momentum and to more powerfully and quickly actuate the clutch operated upon, so that the response of the mechanism is proportionate to the sudden need for righting the biplane. Thus, with my improved device, there is no tendency of the biplane to oscillate back and forth laterally; the action is purely corrective and markedly gentle and smooth. These qualities are all preserved when the biplane travels in a horizontally curved path. The governing weight, then actuated by centrifugal force, at first causes the clutch acted upon to transmit an amount of power proportionate to the corrective need. As the biplane gradually approaches its proper angle of inclination the amount of power transmitted to the stabilizer planes gradually lessens until it ceases altogether on the biplane coming to a state of equilibrium. So that with my improved device under automatic control, there is a steadiness and gracefulness of flight that is highly desirable.

70 75 80 85 90 95 100 105 110 115 120 125 130 If at any time it is desired to control the stabilizing means by hand, as for instance when the automatic governing means fails to operate sufficiently because of need for adjustment, the operator manually actuates the governing means by operating hand-wheel 51 for stabilizing the machine. If the biplane is inclined downwardly to the left said hand-wheel is rotated in clockwise direction, rotating sleeve 48 and drum 52 fixed thereto in the same direction, and winding wire 53 on said drum and unwinding wire 54 therefrom, until stop 76 of wire 53 encounters guide bolt 55, when spring 59 will be distended and the slackness of chain 65 and spring 67 taken up. Said spring 67 will then be distended, and weight 29, or weight 78, pulled to the left with more than the usual force, when clutch 20 will be caused to transmit more power than usual to stabilizer planes 41 and 44, thus pulling stabilizer

plane 41 downwardly and stabilizer plane 44 upwardly to their extreme positions. If the biplane is inclined downwardly to the right, hand-wheel 51 is rotated in anti-clockwise direction, when the opposite action to that just described takes place.

The extreme positions of said stabilizer planes 41 and 44 in either direction are determined by stop members on their respective operating wires coming in contact with the respective guide pulleys over which said wires run, as stop member 90 of wire 43 of stabilizer plane 41 coming in contact with guide pulley 91 of said wire. Whenever said stabilizer planes are stopped in either of their extreme positions by said stop members, the transmitting clutch then in operation will slip, as the resistance to the operation of said clutch will be greater than its capacity of transmission. This condition, however, rarely occurs and, as a rule, only when the controlling means is under manual operation. Ordinarily, when the stabilizer plane actuating means is under automatic control, the stabilizer planes do not reach their extreme positions, as the biplane is in the act of being righted before this occurs. Under normal conditions and automatic control the angular movement of said planes is but little.

If, after the operator has rotated hand-wheel 51 and the stabilizer planes have moved to either of their extreme positions, it is desired to retain said planes in said positions for a more or less extended period, the operator then presses foot lever 72 downwardly with his foot, when non-rotatable cone clutch member 70 will engage upstanding clutch portion 69 of drum 52 and hold said drum against rotation, thus locking the several parts in their then positions and freeing the hand of the operator. Upon the need for manual control of the governing means ceasing the operator removes his foot from foot lever 72, when the several parts of the manual mechanism return to their normal positions and the governing means is freed for automatic operation.

I claim:

1. A flying machine stabilizer including in combination power driven means comprising two shafts adapted for synchronous rotation in the same direction, a drum mounted for rotation in either direction, a clutch on each of said shafts for transmitting rotation to said drum, reversing means between one of said clutches and said drum, an oscillatable stabilizer plane, a wire wrapped around said drum and having its ends connected to the top and bottom respectively of said plane, a weight movable laterally of the stabilizer, and means on said movable weight for at one time operating one of said clutches to rotate said drum in one direction and at another time operating

the other of said clutches to rotate said drum in the opposite direction.

2. A flying machine stabilizer including in combination power driven means comprising two shafts adapted for synchronous rotation in the same direction, a drum mounted for rotation in either direction, a clutch on each of said shafts for transmitting rotation to said drum, reversing means between one of said clutches and said drum, two oscillatable stabilizer planes, a wire wrapped around said drum in one direction and having its ends connected to the top and bottom respectively of one of said planes and another wire wrapped around said drum in the opposite direction and having its ends connected to the top and bottom respectively of the other of said planes, a weight movable laterally of the stabilizer, and means on said movable weight for at one time operating one of said clutches to rotate said drum in one direction and at another time operating the other of said clutches to rotate said drum in the opposite direction.

3. A flying machine stabilizer including in combination power driven means comprising two shafts adapted for synchronous rotation in the same direction, a drum mounted for rotation in either direction, a clutch on each of said shafts for transmitting rotation to said drum, reversing means between one of said clutches and said drum, two oscillatable stabilizer planes, means operatively connecting said drum with said planes for synchronously moving each plane in a direction opposite to that of the other plane upon rotation of the drum, a weight movable laterally of the stabilizer, and means on said movable weight for at one time operating one of said clutches to rotate said drum in one direction and at another time operating the other of said clutches to rotate said drum in the opposite direction.

4. A flying machine stabilizer including in combination power driven means comprising two shafts adapted for synchronous rotation in the same direction, a drum mounted for rotation in either direction, a clutch on each of said shafts for transmitting rotation to said drum, reversing means between one of said clutches and said drum, an oscillatable stabilizer plane, a wire wrapped around said drum and having its ends connected to the top and bottom respectively of said plane, a weight movable laterally of the stabilizer, and wedges on said movable weight for at one time operating one of said clutches to rotate said drum in one direction and at another time operating the other of said clutches to rotate said drum in the opposite direction.

5. A flying machine stabilizer including in combination power driven means comprising two shafts adapted for synchronous rotation in the same direction, a drum mounted for

rotation in either direction, a clutch on each of said shafts for transmitting rotation to said drum, reversing means between one of said clutches and said drum, two oscillatable stabilizer planes, a wire wrapped around said drum in one direction and having its ends connected to the top and bottom respectively of one of said planes and another wire wrapped around said drum in the opposite direction and having its ends connected to the top and bottom respectively of the other of said planes, a weight movable laterally of the stabilizer, and wedges on said movable weight for at one time operating one of said clutches to rotate said drum in one direction and at another time operating the other of said clutches to rotate said drum in the opposite direction.

6. A flying machine stabilizer including in combination power driven means comprising two shafts adapted for synchronous rotation in the same direction, a drum mounted for rotation in either direction, a clutch on each of said shafts for transmitting rotation to said drum, reversing means between one of said clutches and said drum, two oscillatable stabilizer planes, a wire wrapped around said drum in one direction and having its ends connected to the top and bottom respectively of one of said planes and another wire wrapped around said drum in the opposite direction and having its ends connected to the top and bottom respectively of the other of said planes, a weight movable laterally of the stabilizer, and wedges on said movable weight for at one time operating one of said clutches to rotate said drum in one direction

and at another time operating the other of said clutches to rotate said drum in the opposite direction, the operation of said clutches by said wedges being proportionate to the variation of the stabilizer laterally from its normal.

7. A flying machine stabilizer including in combination power driven means comprising two shafts adapted for synchronous rotation in the same direction, a drum mounted for rotation in either direction, a clutch on each of said shafts for transmitting rotation to said drum, reversing means between one of said clutches and said drum, two oscillatable stabilizer planes, means operatively connecting said drum with said planes for synchronously moving each plane in a direction opposite to that of the other plane upon rotation of the drum, a weight movably laterally of the stabilizer, and means on said movable weight for at one time operating one of said clutches to rotate said drum in one direction and at another time operating the other of said clutches to rotate said drum in the opposite direction, the operation of said clutches by the means on said movable weight being proportionate to the variation of the stabilizer laterally from its normal.

Signed at New York, in the county of New York, and State of New York, this 22 day of March, 1915, before two subscribing witnesses.
